CLAIM

The ornamental design for a sun visor as shown and described.

DESCRIPTION

FIG. 1 is a top, front, left side perspective view of a sun visor showing my new design in its environmental use;

FIG. 2 is a top plan view thereof, the bottom plan view being a mirror image of FIG. 2;

FIG. 3 is a front elevational view thereof;

FIG. 4 is a back elevational view thereof; and,

FIG. 5 is a right side elevational view thereof, the left side elevational view being a mirror image of FIG. 5.

The broken lines showing glasses in FIG. 1 illustrate environment and form no part of the claimed design. All other broken lines in the drawings illustrate stitching and form part of the claimed design.
